PILOT AND COUPLER STRUCTURE

Harry A. Hoke, Altoona, Pa., assignor to The Pennsylvania Railroad Company, Philadelphia, Pa., a corporation of Pennsylvania

Application July 17, 1936, Serial No. 91,157

8 Claims.

(Cl. 213—4)

This invention relates to a pilot and coupler structure for a locomotive or the like.

In my pending application for U. S. Letters Patent, Serial No. 83,410, filed June 4, 1936, there is disclosed a locomotive front end construction characterized by a central housing for the reception of the pilot coupler, when not in service, and a pilot having smooth surfaces surrounding the coupler housing and serving to deflect objects away from the track when struck by the locomotive. My present invention provides a cover plate for such a coupler housing, the cover plate being mounted independently of the coupler and adapted for movement about the same pivotal axis, and when closed forming a smooth deflecting surface continuous with the adjacent deflecting surfaces of the pilot.

Among the difficulties encountered in designing a cover plate for such a coupler housing are those which arise from the necessity of providing for vertical adjustment of the coupler. As the coupler shank is raised or lowered on its pivot pin, so as to maintain the correct vertical height of the coupler above the rails incident to changes in the deflection of the locomotive springs, such movement of the coupler should not interfere with accurate fitting of the cover plate in the opening leading to the coupler housing. On the other hand, it is desirable that the cover plate shall be movable with the coupler about the same pivotal axis.

One object of the present invention is to overcome the above recited difficulties by provision of a cover plate mounted independently of the coupler for swinging movement about the same pivotal axis and so arranged that adjustment of the vertical height of the coupler can be effected without disturbing the hinging of the cover plate.

Another primary object of the invention is to provide in a pilot and coupler structure of the character described, an arrangement which permits the use of a standard form of pivoted coupler.

Another object of the invention is to provide, in combination with a coupler housing and cover plate of the character described, a form of uncoupling apparatus which does not require the disconnection of any part when the coupler is housed.

Other objects and advantages of the present invention, including those derived from simplicity and compactness, will be apparent from the description hereinafter set forth of one embodiment of the invention, and a modification there-

of, having reference to the accompanying drawings. Of the drawings:

Fig. I represents a plan view of a locomotive pilot structure embodying the invention, with the coupler and cover plate shown in full lines in service position, and shown in dot-and-dash lines in housed position.

Fig. II represents a front elevation of the same.

Fig. III represents a longitudinal cross section, taken centrally of the pilot, as indicated by the lines III—III of Fig. I.

Fig. IV represents a fragmentary front elevation, with certain parts cut away for clearness of illustration, the coupler being housed and the cover plate being shown in closed position.

Fig. V represents an enlarged longitudinal cross section of the pilot, taken at the coupler pin, and showing the coupler adjusted by means of shims to its maximum elevation within the pilot.

Fig. VI represents an enlarged cross section, taken as indicated by the lines VI—VI of Fig. I, showing details of a locking pin for securing the cover plate in closed position.

Fig. VII represents a rear perspective view of the cover plate.

Fig. VIII represents a plan view of a modified form of coupler and cover plate, in which these parts are connected together with capacity for relative vertical movement; and,

Fig. IX represents a cross section of the pilot, taken at the coupler pin, showing the modified form of coupler and cover plate with these parts in housed position.

With reference particularly to Figs. I and II of the drawings, there is shown a locomotive front end construction which includes an integrally cast pilot and pilot beam. In the particular example shown, the pilot and pilot beam are made up of sections bolted or otherwise secured together, there being a central pilot member 1, and wings 1a, 1b forming lateral extensions of the pilot and pilot beam. It will be understood that the entire structure may be made as an integral casting, and that the particular construction shown in the drawings constitutes merely one example of a locomotive front end construction to which my invention may be advantageously applied.

The top surfaces of the central pilot member 1 and of the wings 1a, 1b, together with a deck plate 2, form a flat deck upon which various equipment may be mounted, including the uncoupling apparatus comprehensively designated at 3. At the front of the pilot, the walls 4a, 4b

converge forwardly toward the center line of the locomotive and present solid deflecting surfaces well adapted to cast an object clear of the track when struck by the locomotive. Desirably steps 5 5 project laterally at each side of the structure near the base thereof. Additional steps 6 in the form of pockets formed in the wing castings 1a, 1b are placed at a higher elevation. In an obvious manner the steps 5, 6 permit a man to mount to the flat deck at the top of the pilot or to gain access to the uncoupling apparatus 3.

In order to accommodate the coupler 7, a housing 8 is provided within the central pilot member 1. As shown most clearly in Figs. III and IV, 15 the pilot member 1 is cellular in construction, and the housing 8 constitutes a compartment bounded at the top and bottom and on all sides except the front by webs or walls of the casting. The housing 8 is of such shape that the coupler 20 7 may be wholly accommodated therein when not in service. At the base of the housing 8, there is a horizontal shelf 9 with an annular boss 10 surrounding the coupler pin 11.

A cover plate 12, the details of which are shown 25 most clearly in Fig. VII, accurately fits the opening at the front of the coupler housing 8. The cover plate 12 includes horizontally projecting hinge lugs 15, 16 which are adapted to surround the coupler pin 11. The lower hinge lug 15 rests 30 directly upon the annular boss 10 at the base of the coupler housing 8, and the upper hinge lug 16 is disposed immediately beneath the roof member 17 of the coupler housing. It may be assumed that the coupler 7 is of standard construction, except that it is desirably provided with a handle 18 for swinging it in and out. Its shank 19 surrounds the pivot pin 11 and has associated therewith shims 19 and a bearing washer 20. In Fig. III the shims 19 are shown placed above the 40 coupler shank 18, whereas in Fig. V the shims 19 are shown placed below the coupler shank 18. The shims 19 thus serve as liners for adjusting the elevation of the coupler 7 with respect to the pilot, and the particular position and number of shims employed may be varied to suit conditions 45 and to give to the coupler 7 the desired vertical height above the rails.

It will be noted that the bearing washer 20 fills the circular opening in the lower hinge lug 15 50 of the cover plate 12, and accordingly the cover plate 12 is not subjected to the weight of the coupler and may turn freely about the coupler pin 11. The circular opening in the upper hinge lug 16 of the cover plate 12 directly surrounds the coupler pin 11. Thus the cover plate 12 may be swung in a horizontal plane about the 55 pivotal axis of the coupler 7, but its vertical height is not dependent upon the position of the coupler 7. Whereas the coupler 7 is rendered 60 vertically adjustable by changing the position of the shims 19, the cover plate 12 is fixed in its vertical position so that when closed it accurately fills the opening at the front of the coupler housing 8.

65 When the coupler 7 is in its lowermost position, as represented in Fig. III and is extended forwardly, the shoulder 22 formed at the base thereof fits a corresponding shoulder formed in the pilot member 1 between the annular boss 10 and the front wall of the pilot. On the other hand, 70 when the coupler 7 is raised to its position of maximum elevation with respect to the pilot, as represented in Fig. V, the clearance beneath the base of the coupler may be taken care of by the 75 insertion of liners 23 extending partway around

the boss 10. The liners 23 are desirably of such construction that they may be readily applied or removed as required. In order that there shall be no obstruction to the movement of the cover plate 12, a portion of the cover plate is cut away 5 at 24, and when the liners 23 are employed they project through this cut away portion of the cover plate 12. At the top of the coupler housing 8, there is provided an arcuate opening 25 which accommodates the link 26 attached to the 10 lifter mechanism of the coupler 7. As the coupler 7 is swung from its service position to housed position, the opening 25 prevents interference 15 with the movement of the link 26. In order to cover the opening 25, the cover plate 12 has at the top thereof a projecting tab 27 which accurately fits the forward portion of the opening 25.

The uncoupling apparatus 3 may take any one of a variety of forms, and in the present example it comprises an operating rod 28 extending across 20 the top deck and terminating at each end in a handle 29. To the central portion of the operating rod 28 there is applied a lever 30 which is joined by a pivot bolt 31 to the yoke portion of an extension arm 32. The extension arm 32 joins 25 the link 26 which in turn is attached to the lifter mechanism of the coupler 7. It will be particularly noted that the pivotal connection between the lever 30 and the extension arm 32 is disposed directly above the axis of the coupler center pin 30 11. Uncoupling is effected by swinging upwardly either of the handles 29 at the ends of the operating rod 28. Moreover, when the coupler 7 is housed within the housing 8, no disconnection is required of any of the parts of the uncoupling 35 apparatus. Such parts are at all times in readiness for service.

In order to limit radial motion of the coupler 7 in a counterclockwise direction, a stop pin 34 is employed, the pin 34 being normally housed in 40 a pocket 35 and secured against removal by means of a collar 36 at the base thereof, as shown most clearly in Fig. III. In its housed position, represented in Fig. IV, the top of the stop pin 34 is beneath the bottom of the coupler. When the 45 coupler is extended forwardly to service position, the pin 34 is raised and turned to the position represented in Figs. I, II and III, wherein its enlarged top portion which is of elliptical cross section rests on the shelf 9 and bears against an up-standing abutment 37. To return the stop pin 34 to housed position, the pin is elevated and rotated clear of the abutment 37 and then dropped into the pocket 35. Radial movement of the coupler 7 in the other direction is limited by the side 55 wall of the coupler housing 8.

When the cover plate 12 closes the opening at the front of the coupler housing 8, it may be locked in position by means of a locking pin 39. The locking pin 39 is secured against removal by 60 means of a cotter 40, and its top is conveniently formed to the shape of a handle 41. The locking pin 39 is adapted to engage an aperture in a projecting flange 42 disposed at the top corner of the cover plate 12. Details of the locking pin 65 39 are shown clearly in Fig. VI.

A modification of the invention is shown in Figs. VIII and IX. The cover plate 12c there shown is substantially similar to the cover plate hereinbefore described, except that instead of being provided with hinge lugs it is secured to the coupler 7c by means of bolts 43. The bolts 43 pass through slots 44 in the face of the cover plate 12, and are adjustable vertically. To provide for such adjustment, wedge-shaped washers 75

45 are desirably employed at each side of the cover plate 12, and a nut 46 is used to draw the washers 45 together. The modified form of cover plate 12c swings with the coupler 7c about the same pivotal axis, but it is capable of adjustment vertically so that the lowering or raising of the coupler 7c will not prevent the cover plate 12c from accurately fitting the opening at the front of the coupler housing 8. To take care of this 10 adjustment of the relative position of the cover plate 12c and the coupler 7c, the bolts 43 are loosened, then moved to the desired position within the slots 44 and then tightened again. Desirably the cover plate 12c is provided with a 15 handle 47 by means of which the coupler and cover plate may be moved simultaneously.

It will be apparent, both with respect to the principal and the modified form of the invention represented in the drawings, that the use of a 20 cover plate for the coupler housing of the type herein described takes care of the problem of raising and lowering the coupler with respect to the pilot without interference with accurate fitting of the cover plate within the opening at the 25 front of the coupler housing. Moreover, when in the closed position the cover plate forms a smooth surface continuous with the adjacent deflecting surfaces of the pilot, so that the front end of the vehicle is devoid of any projecting parts or large 30 openings, and accordingly, there is no danger of objects catching on the front of the vehicle rather than being cast off therefrom.

It will also be apparent that the pilot and coupler structure of this invention does not require 35 any special form of coupler. The cover plate being separate from the coupler, the invention can be readily applied to the standard pivoted couplers now generally used.

While I have described my invention with reference to a specific front end construction, it will be obvious to those skilled in the art that the invention is applicable to many other pilot structures, and that various changes in the elements herein described in detail are contemplated, 45 without departing from the spirit of the invention as defined in the annexed claims.

Having thus described my invention, I claim:

1. A front end structure for a railway vehicle comprising a pilot, a coupler housing therein 50 having an opening bounded by the deflecting surfaces of the pilot, a coupler pivotally mounted on said pilot and movable from a service position, wherein it projects forwardly through said opening, to a position within said housing, and a 55 cover plate for said opening mounted for movement about the same pivotal axis as that of the coupler, said cover plate when closed forming a deflecting surface continuous with the deflecting surfaces of the pilot, and said cover plate and 60 coupler having capacity for relative vertical adjustment.

2. A front end structure for a railway vehicle comprising a pilot and a pilot beam formed integrally therewith, a coupler housing in said pilot 65 having an opening bounded by solid deflecting surfaces, a coupler pivotally mounted on said pilot and adapted for horizontal movement from a service position, wherein it projects forwardly through said opening, to a position within said 70 housing, and a cover plate for said opening, said plate being mounted independently of said coupler for horizontal movement about the same pivotal axis and presenting, when closed, a solid surface continuous with the surrounding deflect- 75 ing surfaces of the pilot.

3. A front end structure for a railway vehicle comprising a pilot, a coupler housing therein having an opening bounded by the deflecting surfaces of the pilot, a coupler pin within said housing, a coupler pivotally mounted on said pin and movable from a service position to a position within said housing, and a cover plate for said opening, said cover plate being mounted for independent rotation on said coupler pin and serving to close the opening of the coupler housing. 10

4. A front end structure for a railway vehicle comprising a pilot, a coupler housing therein having an opening bounded by the deflecting surfaces of the pilot, a coupler pin within said housing, a coupler pivotally mounted on said pin, 15 means on said pin for adjusting the vertical height of said coupler, said coupler being movable from service position to a position within said housing, and a cover plate for said opening, mounted independently of said coupler for movement about the coupler pin, said cover plate serving to close said opening. 20

5. A front end structure for a railway vehicle comprising a pilot, a coupler housing therein, having an opening bounded by the deflecting surfaces of the pilot, a coupler pivotally mounted on said pilot and movable from a service position, wherein it projects forwardly through said opening, to a position within said housing, a stop member movable vertically from beneath said 25 housing to a raised position wherein it limits radial movement of the coupler, and a cover plate for said opening mounted independently of the coupler about the same pivotal axis. 30

6. In a front end structure for a railway vehicle comprising a pilot, a coupler housing therein having an opening bounded by deflecting surfaces of the pilot, a coupler pivotally mounted on said pilot and movable from service position to a position within 40 said housing, a cover plate for said opening, said cover plate being mounted independently of the coupler for movement about the same pivotal axis, and uncoupling apparatus including link members having a pivotal connection about 45 said pivotal axis of the coupler.

7. In a front end structure for a railway vehicle comprising a pilot, a coupler housing therein having an opening bounded by deflecting surfaces of the pilot, a coupler pivotally mounted on said pilot and movable from service position to a position within said housing, a cover plate for said opening, said cover plate being mounted independently of the coupler for movement about the same pivotal axis, uncoupling apparatus including link members having a pivotal connection about said pivotal axis of the coupler, and an 50 arcuate opening in the top of the pilot accommodating the lifter arm when the coupler is in housed position. 55

8. In a front end structure for a railway vehicle, a pilot, a coupler housing therein having an opening bounded by the deflecting surfaces of the pilot, a coupler pivotally mounted on said pilot and movable from a service position to a 65 position within said housing, a cover plate for said opening mounted for movement about the same pivotal axis as that of the coupler, a connection between said cover plate and coupler whereby said parts move together in a horizontal 70 plane but have capacity for relative vertical adjustment, and a handle on the exterior surface of said cover plate. 70
